PIPE WRENCH WITH RATCHET-
CONTROLLED MOVABLE JAW

George Dewey Mead, Crows Landing, Calif.

Application August 27, 1951, Serial No. 243,793

6 Claims. (Cl. 81—100)

1

This invention relates to pipe wrenches, such wrenches including a fixed jaw and a movable jaw mounted for limited swinging or rocking movement relative to the fixed jaw as well as a direct adjusting movement toward or from the same.

The shank of the movable jaw is provided with a row of teeth engaged by a pawl block in such a manner that the shank may be moved freely in a jaw-closing direction but will be held against movement in a jaw-opening direction; and a major object of this invention is to rockably mount this pawl block in the body of the wrench and control the movement of the block in such a manner that while the block normally holds the jaw shank against the frame or body yoke, said shank and block may be rocked with a minimum of friction. At the same time, the block can be instantly pulled clear of the shank when it is desired to allow said shank to be moved lengthwise to open the jaws.

Another object is to provide a wrench of this type in which the body, together with the handle, is a hollow punch-pressed member, the pawl block being completely enclosed and protected in said body, which is strong yet light.

A further object of the invention is to produce a practical wrench and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the improved pipe wrench.

Fig. 2 is a fragmentary longitudinal section of the same with the movable jaw in its normal yoke-engaging position.

Fig. 3 is a similar view showing the movable jaw rocked or swung, as when initially engaging a pipe or the like to be turned.

Fig. 4 is an enlarged cross section on line 4—4 of Fig. 1.

Fig. 5 is a fragmentary section on line 5—5 of Fig. 2.

Referring now more particularly to the characters of reference on the drawings, the wrench comprises a hollow punch-pressed body 1 which includes a rearwardly projecting handle 2, the member 1 having spaced parallel sides 3 between which, at the forward end at the bottom, a short shank block 4 of the fixed jaw 5 is riveted, as at 6. The movable jaw 7 cooperates with the jaw 5 in

2

facing relation thereto and is formed with a shank 8 which extends lengthwise of the wrench body over the jaw 5 and shank 4 and into the body beyond said shank 4, the back edge 9 of the shank 8 normally flatly engaging the flat inner surface of a longitudinal open-ended top yoke 10 formed with and extending between the sides 3; the forward end E of said flat surface being flared, and being a short distance rearwardly of the rear edge of the shank block 4 for a purpose which will be seen.

The edge of the block 4 is curved between its rear edge and the edge which faces the shank 8, as at 11, said curving portion being also preferably transversely curved, as at 12 (see Fig. 5). This curved surface forms a rolling support or fulcrum for the inclined forward end face 13 of a longitudinal pawl block 14. This block is parallel to the shank 8 and has a row of ratchet teeth 15 engaging cooperating teeth 16 on the adjacent facing edge of said shank 8; said teeth being, of course, cut so as to prevent forward movement of the shank.

The pawl block is normally pressed against shank 8 both in a forward longitudinal direction as well as toward the yoke 10 by means of a leaf spring 17 bearing at its free end against the inclined rear end face 18 of the block substantially at right angles to said face; the inclination of the faces 13 and 18 being opposed to each other. The spring is preferably mounted in place at its fixed end by a hook 19 on said end engaged in a notch 20 cut into the bottom face of the block 4 intermediate its ends.

By reason of the above construction and relationship of the parts, the pawl block 14 is constantly urged in an upward and forward direction by reason of the spring action and the inclined forward face 13 of the pawl block bearing against and sliding up the curved surface 12 of the shank block 4. The cooperating teeth of the jaw shank and pawl block are thus held in close but yieldable engagement and at the same time said shank is held flatly against the yoke 10.

By reason of the fact that the forward end E of the flat faced surface is rearwardly of the curved surface 12, said shank can be rocked about said end E as an axis while the pawl block itself rocks about said curved surface 12 both with a minimum of friction.

In order to free the pawl block from the shank teeth to enable the shank to be advanced to open the jaws, said block is provided, intermediate its ends, with a cross pin 21 projecting through slots 22 in the sides 3 for finger manipulation.

Pressure on the cross pin in a direction away from the yoke pulls the pawl block clear of the shank 8 against the resistance of spring 17, allowing said shank to slide forwardly without restraint. Complete withdrawal of the shank 8 from the yoke is prevented by a retaining screw 23 in one side 3 of the body, which screw engages in a longitudinal closed-end groove 24 in the corresponding side of the shank.

The teeth 15 of the pawl block are of inverted form leaving notches 15a therebetween which receive the shank teeth, and as clearly shown in Figs. 2 and 3, the slope of the rear end 18 of the block is less than the slope of the rear side of the notches. This feature of construction enables spring 17 to function to move the pawl-block lengthwise and toward the jaw shank so that all the teeth are held in close contact, and at the same time swinging the jaw 7 to a closed position.

Also, as clearly shown, the forward side of each notch 15a is parallel to the forward end face 13 of the pawl block, so that said block will properly and freely seat itself regardless of wear, while being capable of instant manual withdrawal from the shank when necessary without an accompanying movement of the shank.

From the foregoing description it will be readily seen that there has been produced such a wrench as substantially fulfills the objects of the invention as set forth herein.

While this specification sets forth in detail the present and preferred construction of the wrench, still in practice such deviations from such detail may be resorted to as do not form a departure from the spirit of the invention, as defined by the appended claims.

Having thus described the invention, the following is claimed as new and useful and upon which Letters Patent is desired:

1. A pipe wrench comprising a hollow body formed with a handle and provided with a fixed jaw at its forward end, a movable jaw cooperating with the fixed jaw, a shank projecting rearwardly from the movable jaw and slidably lengthwise through a yoke rigid with the body, a row of ratchet teeth along the edge of the shank opposite the yoke, a pawl block in the body having a row of teeth along one edge facing and normally engaging the shank teeth, an abutment in the body against which the forward end of the block rockably and slidably bears, and a spring in the body engaging and acting on the block and tending to yieldably force the same forwardly and also toward the shank so as to hold the block and shank teeth in engagement and

maintaining the shank in contact with the back of the yoke; the abutment being convexly rounded, and the adjacent end of the block sloping rearwardly from the toothed face of the block.

2. A wrench as in claim 1, in which the forward end of the yoke is slightly to the rear of the point of engagement of the abutment with the block.

3. A wrench as in claim 1, in which the shank teeth are of V form and the pawl block has similarly shaped notches to receive the teeth; one side of the notches being parallel to the slope of said adjacent end of the block.

4. A wrench as in claim 1, in which the rear end of the block slopes forwardly from its toothed face; the spring bearing against such forwardly sloping face substantially at right angles thereto.

5. A wrench as in claim 4, in which the pawl teeth are of inverted V form, leaving notches therebetween to receive the shank teeth; the slope of the rear end of the block being less than the slope of the rear side of the notches.

6. A pipe wrench comprising a body formed with a handle and provided with a fixed jaw at its forward end, the body having a rigid yoke adjacent said jaw, a movable jaw cooperating with the fixed jaw, a shank projecting rearwardly from the movable jaw and slidably lengthwise through the yoke, a row of ratchet teeth along the edge of the shank opposite the yoke, a pawl block having a row of teeth along one edge facing and normally engaging the shank teeth, an abutment rigid with the body against which the forward end of the block rockably and slidably bears, and spring means in the body acting on the block and tending to yieldably force the same forwardly and also toward the shank so as to hold the block and shank teeth in engagement and maintaining the shank in contact with the back of the yoke; the abutment being convexly rounded, and the adjacent end of the block sloping rearwardly from the toothed face of the block.

GEORGE DEWEY MEAD.
